UNITED STATES PATENT OFFICE.

WILLIAM J. HART, OF MOUNT VERNON, NEW YORK, ASSIGNOR TO SPLITDORF ELECTRICAL COMPANY, OF NEWARK, NEW JERSEY, A CORPORATION OF NEW JERSEY.

AUXILIARY STARTING DEVICE FOR INTERNAL-COMBUSTION ENGINES.

1,226,972.

Specification of Letters Patent.

Patented May 22, 1917.

Application filed January 27, 1915. Serial No. 4,634.

To all whom it may concern:

Be it known that I, WILLIAM J. HART, a citizen of the United States, residing at Mount Vernon, in the county of Westchester and State of New York, have invented certain new and useful Improvements in Auxiliary Starting Devices for Internal-Combustion Engines, of which the following is a specification.

My invention relates to apparatus used in starting internal combustion engines, such as used in automobiles and other moving vehicles. It is customary practice, at the present time to start engines of this nature by means of an electric starter but during extremely cold weather, the engine becomes very stiff when not in use for several hours, and the starting motor is not able to turn the engine over at the same speed as when the engine is warm. Further, the air conditions at these times are such as to give poorer carburetion, combining to make starting difficult.

One of the objects of my invention is to decrease this trouble by spraying into the intake manifold or cylinders of the engine a charge of fuel at or about the time the starting motor is put into operation. I have found that if the charge of fuel is first injected into the manifold or into the cylinders, for several seconds of time previous to cranking the engine, that whatever vapor there is produced condenses on the walls of the manifold or cylinders of the engine while some gain is made toward the desired end, the operation is still faulty and I aim to choose, what I call the psychological moment for injecting this fuel into the engine.

A further object of my invention is to break up the fuel into a form of spray so that on the first movement of the engine, the spray is readily mixed with the air in the manifold and will constitute a suitable firing mixture, which is not accomplished by the previous methods of injecting fuel in bulk into the manifold or engine cylinders.

Further and other features of my invention will be readily understood by persons skilled in the art from a consideration of the following description, taken in conjunction with the drawing wherein,

1 represents the engine to which is attached the intake manifold 3. One end of 55 the intake manifold is connected to the car-

bureter 2, having a supply pipe 4 running to the fuel tank. 8 illustrates a certain type of an electrical starting switch fastened to the car by bolts or screws passing through the holes 9. The mechanical mechanism of the starting switch and the connections to the starting motor forms no part of my invention and need not be further described herein. The ignition circuits and in fact, all the electrical circuits used in starting 60 the engine, may also be controlled by the starting switch so that as the foot of the operator is applied to the button 10, the ignition can be switched on and the current from the usual storage battery connected to 65 the starting motor.

Attached to the starting switch 8, by the flanges 12 is an extension 11. The push rod of the starting switch is extended, as shown at 13 and on this extension is 75 mounted a piston which operates within the extension or cylinder 11. Connected to the bottom of the cylinder 11 is a small pipe 17 which in the form shown terminates in the branches 15 and 16, which are 80 adapted to enter openings in the manifold 3. Extending from the fuel bowl of the carbureter 2 is a small pipe 5, terminating in branches 6 and 7. These branches open into branches 15 and 16, respectively, of 85 the pipe 17, just before said branches enter the manifold.

When the foot of the operator is applied to the button 10 of the starting switch 8, the push rod 13 is carried downward and the 90 piston 14 compresses the air in the cylinder 11 and the air is forced through the pipe 17 with considerable force and enters the manifold 3 through the branches 15 and 16. As the air is forced by the opening of the 95 branches 6 and 7, fuel is drawn out of the bowl of the carbureter, through the pipe 5 on account of the suction produced by the air crossing the openings in the branches 6 and 7.

The injection of the fuel into the intake manifold is thus accomplished substantially co-incident with the time when the electrical devices are switched into operation. It is to be understood that the pipes 5 and 17 are 105 to be relatively small so that they do not interfere with the ordinary working of the carbureter but they may be closed off after the engine is started by a device connecting with the starting switch or otherwise. In- 110

asmuch as I have not found it necessary to use means for closing off these auxiliary pipes, I have not shown nor described them herein. The addition of these means are such as may be included in changes and modifications that will suggest themselves to one familiar with devices of this character.

While I have shown the advantage of using my device in one form, it will be apparent to those skilled in the art that numerous changes and modifications may be made without departing from the spirit of my invention or the scope of the appended claims.

Having thus described my invention, what

15 I claim is—

1. In combination, an internal combustion engine having an intake manifold, a carbureter, a pipe leading from the carbureter to said manifold, a source of fuel connected to said carbureter, an auxiliary pipe extending from the fuel supply to said manifold, a starting switch, and means operated by the operation of said starting switch for drawing fuel through said auxiliary pipe and mixing it with air adjacent to the point where said pipe enters said manifold.

2. In combination, an internal combustion engine having an intake manifold, a carbureter connected to said manifold and regularly feeding fuel thereto, a switch for starting the engine, an air compressor operated by said switch, said air compressor having a direct connection with said manifold, and an auxiliary connection between said carbureter and manifold, whereby when said switch is actuated air is forced from said compressor and fuel is drawn through said auxiliary connection to mix with each other and enter said manifold.

3. In combination, an internal combustion engine, a carbureter having a main connection thereto, a switch for starting said engine, an air compressor operated by said switch, a pipe leading from said air compressor to said engine and an auxiliary pipe 45 leading from said carbureter into the first mentioned pipe at a point near where said pipe enters said engine.

4. In combination, an internal combustion engine, having an intake manifold, a carbureter connected to said manifold and to a source of fuel supply, a switch for operating electrical circuits for starting said engine, an air compressor operated by said switch, a pipe leading from said air compressor to said manifold and an auxiliary pipe leading from the fuel supply into the first mentioned pipe near said manifold.

5. In combination, an internal combustion engine, having an intake manifold, a carbureter regularly feeding fuel to said engine manifold, a switch having a push rod for controlling the electrical circuits used in starting said motor, an air compression chamber attached to said switch, a piston 65 within said chamber and mounted on the end of said push rod, an air pipe extending from said chamber to said manifold and an auxiliary pipe in shunt to said carbureter terminating in the first mentioned pipe near 70 said manifold for the purpose described.

In testimony whereof I have affixed my signature in the presence of two witnesses.

WILLIAM J. HART.
